UNITED STATES PATENT OFFICE

2,061,253

AMUSEMENT APPARATUS

David C. Rockola, Chicago, Ill.

Application June 29, 1935, Serial No. 29,039

5 Claims. (Cl. 273—1)

This invention relates to amusement apparatus.

It is an object of this invention to provide an improved amusement apparatus which is relatively simple and inexpensive in construction and 5 efficient in use.

Another object of the present invention is to provide a combination free play device and ticket dispensing device for an amusement game apparatus of the so-called pin and marble game type.

10 An additional object of the present invention is to provide, in a so-called pin and marble game, a combination free play and ticket vending device by means of which the player may, at his election, either choose to play a predetermined 15 number of free games which he may have to his credit or elect to have a ticket or tickets vended to him from the device and redeemable in merchandise or the like.

An additional object of the present invention 20 is to provide an improvement upon a certain feature of the free play or free game device shown and described in Patent No. 1,985,736 granted to William H. Bellah on December 25, 1934, on a game apparatus.

25 Another object of the present invention is to provide an improved device for moving the so-called "free game" registering dial (32) of the game apparatus shown and described in the above-identified Bellah patent in circumferential steps in a direction back toward its initial or 30 zero position.

Other objects will appear hereinafter.

The invention consists in the novel combination and arrangement of parts to be hereinafter 35 described and claimed.

The invention will best be understood by reference to the accompanying drawings, showing the preferred form of construction and in which:

Fig. 1 is a fragmentary plan view of a game apparatus embodying a preferred form of the present invention;

Fig. 2 is a vertical sectional view, on line 2—2 in Fig. 1, showing certain parts of the free play device and the operating lever for the ticket vending device;

Fig. 3 is a sectional view, on line 3—3 in Fig. 1, showing certain parts of the ticket-vending device;

Fig. 4 is a sectional view, showing certain parts 50 of the ticket vending device;

Fig. 5 is a perspective view of certain parts of the ticket web advancing device embodied in the present invention;

Fig. 6 is an elevational view, similar to Fig. 55 5

Fig. 7 is a vertical sectional view on line 1—1 in Fig. 1, and showing a pressure member adapted to bear against the ticket web;

Fig. 8 is a vertical sectional view, on line 8—8 in Fig. 1.

A fragment of the game apparatus shown and described in the above-identified patent to William H. Bellah, No. 1,985,736 is shown in the drawings, is therein generally indicated at 10, and comprises a cabinet 11 in which is arranged a 10 horizontal shaft 12, and carried by, and fixed to, the shaft 12, in the cabinet 11, is a "free game" registering dial 13 which corresponds to the "free game" dial 32 in the above-identified Bellah patent.

Likewise carried by the shaft 12, and fixed thereon, is a ratchet 14 which corresponds to the ratchet 41 in the above-identified Bellah patent.

In the Bellah patent above referred to, the 20 free game registering dial (13 here, 32 in the patent) may be moved, in circumferential steps, in a direction back toward its initial or zero position, by the proprietor of the game apparatus, through the manipulation of a handle 25 80 which is carried by the shaft 27 of the device of the patent, this handle projecting exteriorly of the cabinet (the reference numerals above given being those of the patent).

In order to move the free game registering dial 30 13 of the present apparatus in circumferential steps, in a direction back toward its initial or zero position, there is mounted on the shaft 12 a handle or arm 15, and the lower end portion 16 of this handle 15 projects downwardly below 35 the bottom wall 17 of the cabinet 11, through a slot 18 which is formed in a plate or housing 19, the plate 19 being attached to the bottom wall 17 of the cabinet on the upper side of the latter. This handle 15—16 "floats", that is, is loosely 40 mounted on the shaft 12.

Likewise "floating", that is, loosely mounted on the shaft 12 which carries the free game registering dial 13 is an arm 20 and pivotally connected to this arm 20, as at 21, is a pawl 22.

The pawl 22 has a lateral extension or pin 38 attached thereto (Fig. 2) and this pin 38 is engageable with a cam 39, the cam 39 being formed on a supporting frame 36 which is mounted in the cabinet 11; and the pawl 22 has an angled end portion 41 which is engageable with the teeth of the ratchet 14.

A coil spring 23 has one end attached to the arm or lever 15 and this spring 23 has its other 50 55 end attached to the frame 36.

end attached to a lateral extension 24 of the arm 20 (Fig. 2).

A coil spring 28 has one end attached to a pin 74 which projects laterally from the arm 20 (Figs. 5 1 and 2) and the other end of this spring 28 is fixed in the cabinet 11.

The arm 20 has an upward extension 29 and this extension 29 is engageable with a lateral extension or pin 30 which is carried by a latch member 31, this latch member 31 being pivotally mounted in the cabinet 11, as at 32, and having an angled end portion or arm 33 which is engageable, in a manner to be described more fully hereinafter, with the inner end portion of the coin 15 slide 34, the coin slide 34 being slidably mounted in the end wall 35 of the cabinet 11.

A coil spring 37 has one end mounted on the supporting frame 36, which is arranged in the cabinet 11, and this coil spring has its other end 20 attached to the pawl 22 (Figs. 1, 2 and 3).

The lateral extension 24 of the arm 20 normally engages a resilient contact or circuit-closing device 40, which is mounted in the cabinet 11, so as normally to maintain the latter in closed 25 circuit position.

The present invention has, as one of its objects, as has been stated hereinbefore, to provide a novel ticket-dispensing or web-advancing device for dispensing a ticket or portion of an inscription-bearing 30 web from the cabinet 11 to the player, if the player elects to receive such a ticket or tickets, which may be redeemed for merchandise or the like, rather than to play a corresponding number 35 of free games, which the player may have to his credit, upon the apparatus.

To this end there is provided in the end wall 35 of the cabinet 11 a ticket-dispensing outlet or slot 41 (Fig. 3) and adapted to be dispensed exteriorly 40 of the cabinet 11, through this slot 41, is the free end portion 42 of an inscription-receiving or inscription-bearing web 42. This web 42 is guided over a horizontal shelf 43 (Fig. 3) and is advanced, in a step by step movement, by a web-advancing roll 44, this roll 44 being provided with 45 lugs 45 which engage in corresponding perforations 46 which are formed in the web 42. The web 42 likewise works around a guide roller 47 and is guided across the bottom wall 17 of the cabinet 11 (Fig. 3).

50 The web-advancing roll 44 is mounted on a horizontal shaft 48 (Figs. 3 and 7) and likewise carried by this shaft 48 is a ratchet 49, carried by, and projecting laterally from, the ratchet 49 are pins or lugs 50 which are arranged at radial 55 intervals around and relative to the ratchet 49.

Engageable with the pins 50 is a pawl 51 which is pivotally mounted, as at 52, upon a slide bar 53, this slide bar 53 being slidably mounted upon a vertical supporting wall 54 which is arranged in 60 the cabinet 11. This slide bar 53 has an angled or lateral extension 55 (Fig. 5) and the pawl 51 normally rests upon this extension 55 of the slide bar 53, movement of the pawl 51 (clockwise, Fig. 5) being limited by a laterally projecting portion 65 or arm 66 of the vertical wall 54.

Pivots connected to the slide bar 53, at one end of the latter, as at 68, is a link 55, and this link 55 has a pin and slot connection 56-57 with an extension 58 of the arm 20 (Fig. 1).

70 Pivots mounted at one end, as at 62, on the vertical supporting wall 54, is a latch member 58 and mounted on this latch member 58 is a pin 59 which is engageable with a cam or beveled edge portion 60 of the pawl 51.

75 Provided in the peripheral edge of the ratchet

49 are notched or cut-out portions 61 and engageable in these notched or cut-out portions 61 is a roller 63 which is mounted upon one end portion of a latch dog 62 which is pivotally mounted, as at 64, upon the vertical supporting wall 54.

The slide bar 53 is slidably mounted at one end (left hand end is seen in Fig. 4) upon the vertical supporting wall 54, by means of a pin and slot connection 63-65, (Fig. 4) and at its other end (right hand end, Fig. 4) the slide bar 53 is slidably mounted upon the supporting wall 54 by means of the extension 55 which projects through a slot 56 which is formed in the wall 54, and associated with the slide bar 53 is a conventional full stroke device 66-68 (Fig. 5).

Pivots mounted on the inner side of the end wall 35 of the cabinet 11 (Fig. 1), between its ends, as at 67, (Fig. 7), is a pressure member 68 which includes an end portion 69 which normally bears upon the ticket web 42 (Fig. 7). Attached to the end portion 69 of the pressure member 68 is a coil spring 70 which normally urges the pressure member 68 in a direction (clockwise, Fig. 7), to move the end portion 69 thereof out of engagement with the ticket web 42, the end portion 69 of the member 68 being moved into engagement with the web 42 by means of an arm or pin 71 which is attached to the free game registering dial 13, this pin 71 being engageable with an angled or offset end portion 72 of the pressure member 68.

Operation

In the use of the present game apparatus the free game registering dial 13 may be rotated in 35 circumferential steps in a direction away from its initial or zero position by the means shown in the above-identified Bellah patent, or in any other suitable manner, so as to indicate the number of free plays which the player may have to his credit at any time, and in order to move the 40 free game registering dial 13 in circumferential steps back toward or into its initial or zero position (in a clockwise direction, as seen in Fig. 2) the proprietor of the present game apparatus may 45 reach under the bottom wall 17 of the cabinet 11 and grasp the lower end portion 16 of the handle 15 and pull or pivot the same (from full to dotted line position, (Figs. 2 and 3)).

This movement of the handle 15-16 (from full to dotted line position, (clockwise, Fig. 2), 50 tensions the coil spring 23 and the latter, when thus tensioned, acts to pivot the arm 20 attached thereto, at 12 (in a clockwise direction, Fig. 2). During this movement of the arm 20 and the pawl 22 (from full to dotted line position, Fig. 52), the spring 37 acts upon the pawl 22 to pivot the same, at 21, upon its supporting arm 20, (clockwise, Fig. 2), thereby moving the angled end portion 41 of the pawl 22 (Fig. 1) into engagement with the teeth of the ratchet 14 which is fixed to the shaft 12, which carries the "free game" registering dial 13, whereupon this movement of the pawl 22, thus disposed in engagement with the teeth of the ratchet 14, moves the ratchet 14, shaft 12, and the "free game" 60 registering dial 13 (in a clockwise direction, Fig. 2), thereby moving the "free game" registering dial 13 a predetermined circumferential distance or step (clockwise, Fig. 2) back toward its initial or zero position and thus, in effect, subtracting one 65 free game from the total number of free games which the player may have to his credit, as indicated by suitable markings which may be inscribed on the "free game" registering dial 13.

After the completion of its operative stroke, 75

as above set forth, the arm 20 and the pawl 22, which is attached thereto, are reset back into their initial position, (as in full lines, Fig. 2), by operation of the tensioned coil spring 28, and the handle 15-16 is reset back into its initial position, (as in full lines, Fig. 2), by means of the tensioned coil spring 23. During this resetting movement, the pin 38, which is carried by the pawl 22, rides over the cam 39 and this movement of the pin 38 over the cam 39 pivots the pawl 22 out of the engagement with the teeth of the ratchet 14 so that the ratchet 14, shaft 12, and "free game" dial 13 may be operated (in a counterclockwise direction, Fig. 2), and in circumferential steps in a direction away from its initial or zero position, by means of the apparatus shown and described in the above identified Bellah patent No. 1,985,736, so as to indicate the number of free games the player may have to his credit at any time.

As the handle 15-16 is moved (from full to dotted line position, Fig. 2), to effect the operation of moving the free game dial 13 a predetermined circumferential distance back toward its initial or zero position, the upper end portion 29 of the arm 15-16 engages the laterally extending pin 30 which is carried by the pivotal latch dog 31, and thereby pivots the latch dog 31, at 32, (in a counterclockwise direction, Fig. 2). This movement of the dog 31 raises the angled end portion or arm 33 thereof up into a position in front of, or in engagement with, the inner end portion of the coin slide 34, thereby preventing fraudulent operation of the coin slide 34 and the operating mechanism 15-16-77 etc. (Fig. 2) of the game apparatus, associated therewith, during the operation of moving the handle 15-16 and associated parts, that is, during the operation of moving the free game registering dial 13 in circumferential steps back toward or into its initial or zero position.

As the arm 20 is moved (clockwise, Fig. 2), by operation of the handle 15-16, the angled end portion 24 thereof moves out of engagement with the resilient contact or circuit closing member 40, whereupon the member 40 moves, by its arm resiliency, into open circuit position so as to open the electromagnetic operating circuit shown and described in the above-identified Bellah patent, this preventing fraudulent operation of the game apparatus during the operation of moving the free game registering dial resetting device 15-16-20-22, etc.

In the event that the player of the game apparatus which embodies the present invention elects to receive a ticket or tickets from the machine, rather than to play a number of free games, which he may have to his credit, upon the apparatus, the proprietor of the machine may, by manipulating the handle 15-16, project the free end portion of the web 42 (Fig. 3) out through the dispensing slot 41 and, it will be noted, that this movement of the handle or lever 15-16 will not only move the free game registering dial 13 a predetermined circumferential distance back toward its initial or zero position (clockwise, Fig. 2) but will also dispense a predetermined length of the web 42 out through the dispensing slot 41.

The foregoing movement of the handle 15-16 (clockwise from full to dotted line position, Fig. 2) acts through the extension 81 of the arm 20 to move the pin 56 in the slot 57 (right to left, Figs. 3 and 5) and when the pin 56 reaches the end of the slot 57 it acts to move the link 55

(right to left, Figs. 3, 4, and 5) and this movement of the link 55 (right to left, 3, 4 and 5) acts upon the pin 80 to move the slide bar 53 (right to left, Figs. 4, 5 and 6). During this movement of the slide bar 53 (right to left, Figs. 4, 5 and 6), the cam or beveled edge 60 of the pawl 51 which is carried by the slide bar 53, engages the pin 59 and thereby pivots the dog 58 out of latching engagement with the corresponding notched portion 61 of the ratchet 49; and upon further movement of the slide bar 53 (right to left, Figs. 4, 5 and 6) the end edge 68 of the pawl 51 engages one of the lugs 50 in the ratchet 49 and thereby rotates the latter a predetermined circumferential distance (counterclockwise, Fig. 5). This movement of the ratchet 49 (counterclockwise, Fig. 5) moves the latch dog 62 out of engagement with the corresponding notched portion 61 of the ratchet 49, against the action of its resetting spring 86.

In this manner the ratchet 49, shaft 48, and web-advancing roll 44 are moved a predetermined circumferential distance (counterclockwise, Figs. 3, 4, 5 and 6), thereby advancing the free end portion of the ticket web 42 a predetermined circumferential distance out through the dispensing slot 41, whereupon the player may tear or sever the free end portion of the ticket web 42 from the body of the same, and redeem the ticket or tickets thus vended, in merchandise or the like, from the proprietor of the machine.

It will be seen, therefore, the player may, at his election, either play upon the machine the number of free games which he may have to his credit, as indicated by the free game registering dial 13, or at his election, receive an equivalent number of merchandise tickets, from the web 42, which may be dispensed to him through the dispensing slot 41, in the manner hereinbefore set forth, and it will be noted that if the player elects to receive a ticket or tickets from the web 42, rather than to play upon the machine the number of free games he may have to his credit, the operation of dispensing the ticket or tickets through the dispensing slot 41, by manipulating the handle or lever 15-16, also acts to subtract one game from the total number of free games which the player may have to his credit, is indicated by the free game registering dial 13, since each operation of the handle lever 15-16 moves the free game registering dial 13 a corresponding circumferential distance or step back toward its initial or zero position (clockwise, Fig. 2), as hereinbefore explained.

It will be noted by reference to Fig. 6 that when the slide bar 53 is retracted from full stroke position (as in full lines, Fig. 6) back into its initial or normal position (as in dotted lines, Fig. 6), the pawl 51 will ride over the particular pin 50 on the ratchet 49 which is disposed in engagement with the lower edge of the pawl 51 and at the same time the upper edge of the pawl 51 will bear against the lateral projection 64 of the wall 54, so that the movement of the pawl 51 about its pivot 52 is thus effectively guided between the parts 50 and 64 and the effective movement of the pawl 51 and associated parts, including the ratchet 49, shaft 48 and web-advancing roll 44 are thus limited. In this manner fraudulent operation of the web-advancing roll 44, that is by pulling upon the web 42, is prevented.

However, as the parts are returned to their initial position (as in full lines, Fig. 4) the latch 58 will drop by gravity back into the notched portion

61 of the ratchet 49 and thus latch the ratchet 49 and associated parts against operation.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such 10 variations and modifications as come within the scope of the appended claims.

Having thus described my invention what I claim as new and desire to protect by Letters Patent is:

- 15 1. An operating mechanism for an amusement apparatus of the type which includes a cabinet having a free game registering dial and a ticket dispensing device mounted therein, said operating mechanism including means for moving the 20 said free game registering dial in circumferential steps in a direction back toward its initial position, and means coacting with the said first-named means, when the latter is operated, for operating the said ticket dispensing device in a direction to 25 dispense a ticket from the said cabinet.
2. An operating mechanism for an amusement apparatus of the type which includes a cabinet having a free game registering dial and a ticket dispensing device mounted therein, said operating 30 mechanism comprising means, including a manually operable member projecting downwardly in the said cabinet so as to be accessible from the bottom of the latter, for moving the said free game registering dial in circumferential steps 35 in a direction back toward its initial position, and means coacting with the said first-named means, when the latter is operated, for operating the said ticket dispensing device in a direction to dispense a ticket from the said cabinet.
- 40 3. An operating mechanism for an amusement apparatus of the type which includes a cabinet having a free game registering dial and a ticket dispensing device mounted therein, said operating mechanism comprising means, including a horizontally extending shaft arranged in the 45 said cabinet and having said dial fixedly mounted thereon, a manually operable member pivotally

mounted on said shaft for movement relative thereto and having a handle portion projecting downwardly in the said cabinet so as to be accessible from the bottom of the latter, for moving the said free game registering dial in circumferential steps in a direction back toward its initial position, and means coacting with the said first-named means, when the latter is operated, for operating the said ticket dispensing device in a direction to dispense a ticket from the said cabinet. 5 10

4. In a game apparatus of the type having a free game control with an indicating drum and mechanism operable by playing of said game for moving said drum in steps from an initial position to indicate free plays scored by the player, free play mechanism comprising: manual means for resetting said indicating drum to said initial position in steps, and a ticket issuing mechanism including a rotatable ticket feed having driving connection with said manual resetting means and operable to feed one ticket with each resetting step of said drum, but inoperable when the said indicating drum is advanced to indicating positions as aforesaid. 15 20 25

5. In a game apparatus of the pin and marble type having a free play control operable by the playing of said game apparatus to indicate the number of free plays scored by the player and to release said game apparatus for a number of free plays corresponding to the number indicated by said control means, free play ticket mechanism comprising: a rotatable free play indicating drum operable by playing of said game apparatus and having means releasing said apparatus for a number of free plays corresponding to the indication of said drum; manually operable means for resetting said drum from a free play indicating position to an initial position; and ticket issuing mechanism including a member movable to issue tickets corresponding in number to the number of free games indicated by said drum and having driving connection with said manual means for operating said movable member when the said drum is reset. 30 35 40 45

DAVID C. ROCKOLA.
